MECHANICAL TOY

Edward Rocuskie, New York, N. Y.

Application January 9, 1937, Serial No. 119,846

7 Claims. (Cl. 272—31)

The present invention relates to a new and improved mechanical toy.

The primary object of the invention is to provide a mechanical toy vehicle supported on a turn-table or the like, with means provided for controlling rotation of the turn-table and the steering of the vehicle thereon.

A further object is to provide a rotatable turn-table with a mechanical toy vehicle supported thereon, the surface of the turn-table having a series of hazards forming a part thereof, remote control means being provided for steering the vehicle so as to avoid the hazards during the rotation of the turn-table.

15 The invention will be fully and comprehensively understood from a consideration of the following detailed description when read in connection with the accompanying drawings which form part of the application.

20 In the drawings:

Fig. 1 is a perspective view of the mechanical toy with parts broken away to illustrate the interior mechanism thereof.

Fig. 2 is a perspective view of the means for 25 steering the vehicle; and

Fig. 3 is a perspective view, partly in section, of the toy vehicle.

Referring to the drawings for a more detailed description thereof, the numeral 5 indicates the 30 box-like structure of the toy, the same being substantially rectangular shaped and the interior thereof adapted to retain and conceal the mechanism for operating the toy. A rotatable turn-table 6 is mounted on the top surface of the structure 5 and is keyed to the shaft 6', said shaft extending within the interior of the box. Carried by the shaft 6' is a gear wheel 7 in mesh with the worm gear 8 mounted on a longitudinal shaft 9. The longitudinal shaft 9 has one end 35 supported in a bracket 10 extending from the side wall 11 of the box and the other end thereof extends thru the end wall 12 of the box and is journaled therein. As is understood, the shaft 9 is rotatably mounted and for assisting in the 40 rotation thereof there is provided a fly wheel 13 carried by the shaft and mounted between the worm gear 8 and the end wall 12 of the box. Various means may be provided for causing rotation of the shaft, but for purposes of illustration 45 there is disclosed a handle 14 secured to the shaft for manual operation. A spring motor or any other means may be provided for rotating the shaft 9 without departing from the spirit of the invention. Rotation of the shaft 9 thru operation of the handle 14 rotates the worm gear

5 which, thru the wheel gear 7 and shaft 6', causes rotation of the turn-table 6.

A toy vehicle 15 is supported on the turn-table 6 and by means of the steering mechanism, to be later described, is movable across the turn-table as the same is rotated. The steering of the toy vehicle 15 as the turn-table is rotated either clockwise or counter-clockwise thru the shaft 9, causes the vehicle to avoid the series of hazards 16 placed on the surface of the turn-table. The hazards are so positioned that by skillful steering of the vehicle it will follow the highways and avoid contact with the hazards.

The means for steering the toy vehicle is more clearly illustrated in Fig. 2 of the drawings. A 15 transverse slot 17 is provided in the top of the box 5 thru which extends, and is adapted to move therein, a rod 18, said rod being attached to the front end of the vehicle 15 by a universal joint connection 19. It is to be noted that the rod 18 20 extends above the turn-table and has its end bent for attachment to the vehicle, the universal joint connection 19 permitting free movement of the front end of the vehicle should the same contact one of the hazards.

A transverse rod 20 is disposed beneath the slot 17 and has each end thereof secured to the side walls of the box 5. The end of the rod 18 which moves within the slot 17 is anchored to a bearing 21, said bearing being freely movable on the rod 20 and adapted to move thereon during the steering of the vehicle. For steering the vehicle there is provided a shaft 22 having one end thereof freely mounted in a bearing plate 23 secured to the end wall of the box 5 and the opposite end carrying a steering wheel 24. Supported intermediate the ends of the shaft 22 is a block 25 around which is wound an endless cable 26, said cable riding over pulleys 27 secured to each side wall of the box 5. Extending downwardly from the bearing 21 is an arm 28 from which extends at right angles thereto an arm 29 thru which the cable 26 is threaded, said arm 29 being adapted to move with the travel of the cable, thereby moving the bearing 21 along the 40 rod 20. Movement of the bearing 21 causes movement of the vehicle 15 to the right or left along the surface of the turn-table.

The operation of the toy from the above description is believed to be clearly obvious. The 50 player causes rotation of the turn-table by moving the shaft 9 either clockwise or counter-clockwise by rotation of the handle 14. As the turn-table is rotated, the steering wheel 24 is grasped by the player and by turning the same either 55

to the right or to the left, the rod 18 may be caused to move within the slot 17 so as to move the vehicle to either the right or the left to avoid the hazards positioned on the turn-table. Rotation of the steering wheel causes the cable 26 to move over its pulleys 27 and during its movement to urge the bearing 21 along the shaft 20.

In order to maintain the vehicle 15 in constant contact with the surface of the turn-table 6 there is provided a counter-weight 30 which extends at right angles from the bearing 21 and is substantially parallel to the rod 18. It is to be understood that the counter-weight 30 will permit the vehicle to move in a vertical manner as 15 it contacts the hazards but thru the counter-weight will return the vehicle to the surface of the turn-table after its contact with the hazard.

The front end of the toy 15 is shown as being supported on a ball bearing 31 mounted in a 20 receptacle 32. The ball bearing 31 permits free movement of the vehicle over the surface of the turn-table. The rear of the vehicle may be provided with wheels in the usual manner.

It is to be understood that this improvement 25 is capable of extended application and is not confined to the exact showing of the drawings nor to the precise construction described and, therefore, such changes and modifications may be made therein as do not affect the spirit of the 30 invention nor exceed the scope thereof as expressed in the appended claims.

What is claimed as new is:

1. A mechanical toy of the character described, comprising a substantially rectangular box-like 35 structure, a turn-table mounted for rotation on said box, means within said box for rotating said turn-table, a miniature vehicle supported on the surface of said turn-table, and remote control means for guiding said vehicle in a manner to 40 avoid impacting articles held on said turn-table as same is rotated.

2. A mechanical toy of the character described, comprising a substantially rectangular boxlike 45 structure, a turn-table mounted for rotation on said box, said turn-table being supported on a shaft carrying a gear, a transverse shaft rotatably mounted within said box, a worm gear carried by said shaft for engagement with said wheel gear for imparting rotation to said turn-table, 50 a miniature vehicle supported on the surface of said turn-table, and remote control means for guiding said vehicle in a manner to avoid impacting articles held on said turn-table as same is rotated.

55 3. A mechanical toy of the character described, comprising a substantially rectangular box-like structure, a turn-table mounted for rotation on said box, means within said box for rotating said turn-table, an arm extending thru a longitudinal 60 slot in one end of said box and supporting a miniature vehicle in contact with the surface of said turn-table, and remote control means for causing movement of said arm whereby the vehicle is guided as said turn-table is rotated.

65 4. A mechanical toy of the character described,

comprising a substantially rectangular box-like structure, a turn-table mounted for rotation on said box, means within said box for rotating said turn-table, an arm extending thru a longitudinal slot in one end of said box and supporting a 5 miniature vehicle in contact with the surface of said turn-table, a longitudinal shaft supported within said box and substantially parallel with said slot, means for slidably connecting said arm to said longitudinal shaft and remote control 10 means for actuating said slideable connecting means whereby the vehicle is guided as said turn-table is rotated.

5. A mechanical toy of the character described, comprising a substantially rectangular box-like 15 structure, a turn-table mounted for rotation on said box, means within said box for rotating said turn-table, an arm extending thru a longitudinal slot in one end of said box and supporting a 20 miniature vehicle in contact with the surface of said turn-table, a longitudinal shaft supported within said box and substantially parallel with said slot, means for slidably connecting said arm to said longitudinal shaft, remote control 25 means for actuating said slideable connection for guiding said vehicle as said turn-table is rotated, said means including a shaft journaled in one 30 end of said box, a steering wheel attached to the other end of said shaft and an endless cable movable for actuating said slideable connection as the steering wheel is operated.

6. A mechanical toy of the character described, comprising a substantially rectangular box-like 35 structure, a turn-table mounted for rotation on said box, means within said box for rotating said turn-table, a miniature vehicle supported on the surface of said turn-table, means for normally 40 maintaining said vehicle in constant contact with the surface of said turn-table, and remote control means for guiding said vehicle in a manner to 45 avoid impacting articles held on said turn-table as same is rotated.

7. A mechanical toy of the character described, comprising a substantially rectangular box-like 45 structure, a turn-table mounted for rotation on said box, means within said box for rotating said turn-table, an arm extending thru a longitudinal slot in one end of said box and supporting a miniature vehicle in contact with the surface of said turn-table, a longitudinal shaft supported within 50 said box and substantially parallel with said slot, means for slidably connecting said arm to said longitudinal shaft, remote control means for actuating said slideable connection for guiding said vehicle as said turn-table is rotated, said means including a shaft journaled in one end of said 55 box, a steering wheel attached to the other end of said shaft, an endless cable movable for actuating said slideable connection as the steering wheel is operated, and a weighted arm extending 60 at right angles to said longitudinal shaft for normally maintaining said vehicle in contact with the surface of said turn-table.
